UNITED STATES PATENT OFFICE.

SOLOMON R. WAGG, OF APPLETON, WISCONSIN; JAMES B. WAGG ADMINISTRATOR OF
SAID SOLOMON R. WAGG, DECEASED.

PAPER-MAKING APPARATUS.

1,207,451.

Specification of Letters Patent. Patented Dec. 5, 1916.

Application filed November 20, 1913. Serial No. 802,148.

To all whom it may concern:

Be it known that I, SOLOMON R. WAGG, a citizen of the United States, residing at Appleton, in the county of Outagamie and 5 State of Wisconsin, have invented new and useful Improvements in Paper-Making Apparatus, of which the following is a specification.

The present invention has reference to 10 paper-making apparatus, and more especially to apparatus for reeling or winding up the web of paper after the same has been passed through the size bath and before it is subjected to the final drying.

15 It comprehends the provision of improved devices for regulating the speed of the winder proper relative to that of the size rolls, for varying the tension exerted upon the web during winding, and, above 20 all, for smoothing out and removing all wrinkles, creases, puckers and the like in the web prior to winding.

An embodiment of the invention is illustrated in the accompanying drawing, 25 whereof:—

Figure 1 is a diagrammatic side elevation of the complete apparatus; Fig. 2 is an enlarged side elevation of the winding mechanism; Fig. 3 is a plan view of Fig. 2; and 30 Fig. 4 is a transverse section on line 4—4, Fig. 3.

In said drawing, 1 indicates, generally, the strip or web of paper undergoing treatment, and 2 the bath of size through which the 35 same is passed as the initial step of such treatment. This web or strip, which has previously been subjected to the usual, preliminary sizing, with or without mordants, may be led to the starch bath either directly 40 from the machine, or after it has first been reeled up in a dry state.

On leaving the size bath, the web is passed between the rolls 3 and 4, which remove the excess size therefrom, whence it is led, while 45 still wet, first over a guide roll 5, and, next, under a relatively large drum 6, the latter being in the form of a smooth, polished copper cylinder and serving to initially smooth the web and to prepare it for subsequent 50 wet winding. The several rolls and the drum may be mounted in any desired manner, as will be understood.

From the aforesaid drum, the web passes, successively, to the improved take-up,

smoothing, and winding devices or mechanisms, the one first mentioned being constructed with the special object of preventing breakage, relieving shocks and absorbing slack, as well as of insuring rotation of the size rolls and the hereinafter-described 60 winding drum 7 in unison. In the construction illustrated, this take-up or tension device consists of a yieldingly-mounted roll 8 and a horizontally-arranged, rising-and-falling dance roll 9. Roll 8 is carried by a 65 pair of blocks 10, upon which the journal brackets 11 for its trunnions are fixed, and these blocks, in turn, are slidably supported upon a pair of parallel, horizontal rods 12 that pass loosely through transverse openings formed in the blocks, the rear ends of the rods being fastened to a cross-bar 13 supported by inclined brackets 14 from the drum stands 15. The front portions of the rods 12 are encircled by expandible coil 75 springs 16 that are interposed between blocks 10 and the headed rod ends 17, the arrangement being such, therefore, that the said blocks 10, and with them, the roll 8, are normally pressed toward drum 6 by the action of the springs, but are free to move forward, against this pressure, when the tension upon the web increases to a given point. 80

As shown in Fig. 2, the web, on leaving the drum 6, passes upwardly over the roll 8, and thence downwardly beneath and around the rising-and-falling roll 9, whose trunnions are mounted in vertical slots 18 formed in a frame 19. From roll 9, the web passes over the smoothing device, subsequently described, to the drum 7, and then to a reel 20, whereon it is finally wound, while still wet. The drum 7 is rotated through the agency of a cone or other suitable drive 21, capable of operating the drum 95 at different desired speeds, and, in consequence, exerts a positive traction upon the web, which traction or pull is rendered approximately constant by the rolls 8 and 9. These two rolls have a co-operative or complementary action upon the web, the former moving forward and backward toward and from frame 19, and the latter moving upward and downward in said frame, any sudden increase in such traction causing an upward movement of roll 9 which is neutralized by the rearward movement of roll 8 100 produced automatically by the spring 16. 105

Thus the two rolls work oppositely, and, in their action, serve to insure a continuous, regular feed movement of the web, devoid of shocks.

- 5 The smoothing device is located intermediate the winding drum 7 and the frame 19, as previously stated, and in its preferred form, herein depicted, it embodies a pair of rolls 22 and 23, which are mounted upon 10 a cross-bar 24 supported from said frame by brackets 25. This bar is inclined upwardly and forwardly toward said drum, as best shown in Fig. 2, and its upper or front longitudinal edge is disposed in close proximity 15 thereto, while the rolls themselves are arranged at an obtuse angle to each other upon the bar, the apex of such angle being likewise directed toward the drum. The outer ends of the said rolls are journaled in brackets 26 fastened upon the end portions of bar 25, and their inner or confronting ends are journaled in a common, centrally-located bracket 27.

By reason of the angular arrangement of 25 the rolls, the web, in passing thereacross, will be stretched and spread transversely, and in this way all straight wrinkles and puckers in the web will be smoothed out. The action of the spreader is supplemented 30 by means of the winding drum, which is so constructed as to provide for elimination of fine puckers and wrinkles due to the presence of air or of air bubbles under the web. To this end the peripheral wall of the drum 35 is formed with perforations or openings 28, of suitable size and having any desired relative arrangement, and these openings, during the passage of the web thereover, break up the bubbles and permit the air to be 40 dissipated.

The afore-mentioned reel 20 is removably supported in brackets 29, attached to the drum stand 30, so as to permit it to be withdrawn, when filled, and deposited with the 45 web in a wet state thereon upon a frame or rack 31, where it is allowed to remain for a period varying from one to twelve hours, during which step the roll of paper is subjected to a very extended and gradual permeation by the size. In consequence, the 50 tensile strength as well as the ink-resisting property of the paper are increased. The roll is kept wet during this period of rest by being wrapped with wet cloths 32, or in 55 any other desired manner.

After resting in the manner just described, the paper, while still wet, is unreeled and passed over a series of drying rolls 33. It 60 will be understood, therefore, that this final drying does not take place until the period of rest has been completed, during which period the size continues to soak into and be absorbed by the paper, and for this reason the heating and drying are sufficiently 65 remote from the time of immersion in the

size bath to work any injury upon the paper. The rolls 33 are steam heated in any desired manner, and in this connection it may be stated that the continued soaking to which the paper has been subjected precludes 70 possibility of its being injured during drying. This is a matter of especial importance, from an economical standpoint at least, since steam may be utilized as a heating medium, or in other words, a steam drier may 75 be installed, at a very much lower cost than an air drying system, and moreover, the sized paper is rendered proof against ordinary high temperatures by reason of its having been previously subjected to the 80 soaking step or period of rest.

The afore-mentioned frame 31 whereon the wet roll of paper is allowed to rest may be of any suitable construction, but is preferably sufficiently large to enable a number 85 of rolls to be supported thereon at the same time. Also, the rolls may be moved in order through this frame, the paper on the roll at one end of the frame being unreeled and led over the drying rolls. The roll at the 90 other end of the frame is that one which has just been removed from its support in the winding mechanism, it being replaced by the previously emptied reel from the first-mentioned end of the frame. 95

I claim:

1. In an apparatus for winding wet paper web, the combination of a hollow winding drum over which the web passes having its peripheral wall formed with perforations to 100 permit the air to escape from under the web; means for driving said drum; a reel whereon the web is wound; and means for holding said reel against said drum, to cause the latter to drive the former.

2. The combination with means for sizing a paper web, and size expressing means, of a winding drum and coöperative reel driven from the periphery of the drum for winding the wet web into a roll, and automatic tension regulating means coöperative with the web at a point between the size expressing means and the winding drum and embodying a member in engagement with the web and movable in a direction toward and from 110 the winding drum. 115

3. In a machine of the class described, the combination with means for sizing a paper web, and size expressing means, of a winding drum and coöperative reel driven peripherally by said drum for winding the wet sized web into a roll, a roller coöperative with the web at a point between the size expressing means and the winding drum and capable of movement in a direction toward 120 and from the winding drum, and means operative to yieldingly resist movement of said roll toward the winding drum.

4. The combination of means for sizing a paper web, means for winding the wet web 130

into a roll, and means for smoothing the wet sized web prior to winding, comprising rolls arranged to engage the wet web in advance of the winding means and set at reversely inclined positions to the direction of movement of the web.

5. In a machine of the class described, the combination of means for sizing a paper web, coöperative rolls between which the wet sized paper web is adapted to pass and operative to remove the excess size therefrom, and means for winding the wet web, of a polished revoluble cylinder arranged to receive the wet sized paper web from said rolls 10 and operative to smooth the same and to deliver it to said winding means.

6. In an apparatus for winding wet paper web, the combination of a hollow winding drum over which the web passes having its 20 peripheral wall formed with perforations to permit the air to escape from under the web, means for driving said drum, a reel whereon the web is wound, and means for holding said reel against said drum to cause the latter to drive the former and to wind the web 25 under a delivery tension.

7. The combination of means for feeding a wet paper web, a hollow drum arranged to coöperate with said wet web and having its 30 peripheral surface formed with openings therethrough to dissipate air bubbles which form between it and the wet web, and permit the air in said bubbles to escape from under the web, and means for winding the

wet web after passing said drum under regulated tension. 35

8. In a machine of the class described, the combination with means for sizing a web, coöperative rolls between which the wet sized paper web is adapted to pass and operative to remove the excess size therefrom, and means for winding the wet web, of a polished revoluble cylinder arranged to receive the wet sized paper web from said rolls and operative to smooth the same while in 40 actual peripheral surface contact therewith and to deliver said web to said winding means under a pulling and a delivery tension. 45

9. In a machine of the class described, the combination with means for sizing a web, coöperative rolls between which the wet sized paper web is adapted to pass and operative to remove the excess size therefrom, and means for winding the wet web, of a polished revoluble cylinder arranged to receive the wet sized paper web from said rolls and operative to smooth the same while in 50 actual peripheral surface contact therewith and to deliver said web to said winding means under a pulling and a delivery tension. 55

In testimony whereof I have hereunto set my hand in presence of two subscribing witnesses.
